COMBINED HAIR DRYER AND CHAIR

George H. Martin, Chagrin Falls, Ohio, assignor to The Martin Brothers Electric Company, Cleveland, Ohio, a corporation of Ohio

Filed Dec. 15, 1958, Ser. No. 53,780

Term of patent 14 years

(Cl. D15—8)

Fig. 1

The dominant features of the design reside in those portions shown in full lines on the drawing.

I claim:

The ornamental design for a combined hair dryer and chair, as shown and described.
